CLAIM

The ornamental design for a display screen with an animated graphical user interface for a baccarat game, as shown and described.

DESCRIPTION

This application is also related to U.S. Design patent application Ser. No. 29/476,986, filed Dec. 18, 2013, which is a continuation-in-part of the aforementioned U.S. Design patent application Ser. No. 29/467,761. This application is also related to U.S. Design patent application Ser. No. 29/503,743, filed Sep. 29, 2014, which is a continuation-in-part of the aforementioned U.S. Design patent application Ser. No. 29/476,986.

The patent or application file contains at least one drawing executed in color. Copies of this patent or patent application publication with color drawings will be provided by the Office upon request and payment of the necessary fee.

FIG. 1 is a front view of a first image of a display screen with an animated graphical user interface for a baccarat game showing our new design in accordance to a first embodiment;

FIG. 2 is a front view of a second transitioning image thereof;

FIG. 3 is a front view of a third transitioning image thereof;

FIG. 4 is a front view of a fourth transitioning image thereof;

FIG. 5 is a front view of a fifth transitioning image thereof;

FIG. 6 is a front view of a sixth transitioning image thereof;

FIG. 7 is a front view of a seventh transitioning image thereof;

FIG. 8 is a front view of an eighth transitioning image thereof;

FIG. 9 is a front view of a ninth transitioning image thereof;

FIG. 10 is a front view of a tenth transitioning image thereof;

FIG. 11 is a front view of an eleventh transitioning image thereof;

FIG. 12 is a front view of a twelfth transitioning image thereof;

FIG. 13 is a front view of a thirteenth transitioning image thereof;

FIG. 14 is a front view of a first image of a display screen with an animated graphical user interface for a baccarat game showing our new design in accordance to a second embodiment;

FIG. 15 is a front view of a second transitioning image thereof;

FIG. 16 is a front view of a third transitioning image thereof;

FIG. 17 is a front view of a fourth transitioning image thereof;

FIG. 18 is a front view of a fifth transitioning image thereof;

FIG. 19 is a front view of a sixth transitioning image thereof;

FIG. 20 is a front view of a seventh transitioning image thereof;

FIG. 21 is a front view of an eighth transitioning image thereof;

FIG. 22 is a front view of a ninth transitioning image thereof;

FIG. 23 is a front view of a tenth transitioning image thereof;

FIG. 24 is a front view of an eleventh transitioning image thereof;

FIG. 25 is a front view of a twelfth transitioning image thereof; and,

FIG. 26 is a front view of a thirteenth transitioning image thereof.

The broken line showing of the display screen is provided for the purpose of illustrating portions of the article and forms no part of the claimed design.

The appearance of the animated graphical user interface consist of sequential transitions between the images shown in FIGS. 1-13 for the first embodiment and separately between the images shown in FIGS. 14-26 for the second embodiment. The process or period in which one image transitions to another forms no part of the claimed design.
